UNITED STATES PATENT OFFICE

ALBERT H. LANGENHEIM, OF DAYTON, OHIO, ASSIGNOR TO THE DAYTON MALLEABLE IRON COMPANY, OF DAYTON, OHIO, A CORPORATION OF OHIO

This invention relates to lifting jacks. One object of the invention is the provision

One object of the invention is the provision of a lifting jack of simple and economical construction having a novel arrangement of the jack standard and the screw lifting nut providing for ready assembly of the jack parts.

Another object of the invention is the provision of a lifting jack in which the top of the standard and the bottom of the lifting nut have interlocking parts providing for ready assembly of the jack parts.

Other objects and advantages of the invention will be apparent from the following description, the accompanying drawing and the appended claims. In the drawing—

Fig. 1 is a side elevation of a lifting jack embodying the present invention;

Fig. 2 is a central vertical section through the jack; and

Fig. 3 is a top plan view of the standard, the screw and the screw operating parts being removed.

As illustrating a preferred embodiment the invention is shown as incorporated in a single screw jack, especially adapted for use with automobile tires, but, of course, the invention may be incorporated in multiple screw jacks and adaptations thereof.

As shown in the drawing, the jack comprises a hollow standard 10 having a base 11. The standard is preferably a metal casting of integral construction, the main body portion 12 of which is adapted to support the operating devices at its upper end, telescopically receiving the lifting screw.

Loosely mounted within the standard, so as to be telescopically received thereby is an externally threaded lifting screw 16, the threaded portion being of such diameter that it may freely pass through the circular bore 17 which extends longitudinally through the standard. Suitable means are provided to control the movements of the lifting screws, and as the embodiment of the invention illus-

and through bonds' bearded, silvery-brown tree boughs.
The 1,220 is distinguished by its tall, slender, upright
shape, its graceful, slender, slender branches, and its
dark, grey, mottled bark. The trunk is 30 inches
diameter at the ground line, and the tree
is 100 feet high. The trunk is straight, and
the branches are slender, graceful, and
well distributed. The tree is a fine
specimen of its kind, and is a credit to the
State of Oregon.

**6, ASSIGNOR TO THE DAYTON MALLEABLE
PIPE CO., A CORPORATION OF OHIO**

1930. Serial No. 472,791.

The device illustrated has but a single screw, a transversely extending pin 18 passes through the lower end of the lifting screw so as to project from opposite sides thereof, to prevent rotation of the lifting screw, the ends of this pin being received in opposed channels or grooves 20 in the hollow passage in the standard.

In threaded engagement with the lifting screw 16, is a rotatable operating collar or nut 22. The nut is provided with gear teeth 23 which are engaged by the teeth 24 of a driving bevel pinion 25 rotatably mounted on the standard. The driving pinion is provided with a socket 26 of square or irregular cross-section which is adapted to receive the correspondingly shaped end of an operating tool, not shown. The pinion is preferably supported by means of a hollow lug 28 near the top of the standard, having a cylindrical bore 29 which rotatably supports the cylindrical inner end 30 of the pinion. The pinion end has a semi-circular groove 31, and the standard lug 28 has a drilled hole 33 which corresponds with the position of the semi-circular groove 31 so that a pin 34 may be driven through the hole 33 and fit within the groove 31 at the bottom of the pinion to prevent endwise movement of the pinion while permitting free rotational movements thereof.

Heretofore the operating collar or nut of a jack has been held against axial movement by providing an upper extension on the standard so as to overlie the lifting nut. Other arrangements have been employed, but none of them provide a simple and cheap construction permitting the ready assembly of the operating parts. In accordance with the present invention, however, the jack standard is of very simple and cheap construction, having no upward extensions overlying the top of the lifting nut to hold it down against axial movement. As shown in Fig. 2 the standard has a top flat surface 37, and the sides of the upper end of the stand-

ard are cylindrically formed throughout the major extent thereof, as indicated at 38. One side of the standard top, however, projects outwardly to form an overhanging lug 39, this lug being provided preferably on the side of the jack above the driving pinion 25, but it may be located in any convenient position. The bottom of the nut is hollow so that a cylindrical bearing surface 40 is provided at the lower end of the nut, in bearing engagement with the cylindrical portion 38 just below the top of the standard. Just above the bearing surface 40 the nut is inferiorly grooved as indicated at 41, the shape of the groove being such that it may receive the lug 39 of the standard, as shown. The lower portion of the groove 41 bears against the bottom of the lug 39 and at this point it will be understood that the nut is prevented from moving vertically upwardly with respect to the standard. The nut, however, may be readily applied to the top of the standard before the lifting screw 16 is in threaded engagement with the nut. If it is assumed that the nut 16 is entirely removed, and the pinion 25 is also removed from the standard, it will be apparent that the nut may be tilted so as to raise the right-hand side of the nut as viewed in Fig. 2, the nut pivoting about its interlocking engagement with the top of the standard at lug 39, and the nut may then be moved laterally in its tilted position so as to disengage the interlocking parts at the bottom of the nut and the top of the standard.

The nut 22 has a downwardly facing bearing surface 43, and while this surface may rest directly on the top of the standard to engage the flat surface 37 provided thereon, an antifriction bearing is preferably interposed between these two surfaces 43 and 37. This bearing is shown at 44 and preferably comprises upper and lower bearing races and a number of balls or rollers therebetween. The antifriction bearing, of course, materially reduces the friction and provides for easy operation of the jack.

It will now be apparent that the various parts of the jack may be very readily assembled. The nut 22 with the antifriction bearing parts in place, is first applied to the top of the standard by moving it laterally while in an inclined attitude to engage the standard lug with the groove in the nut, and then tilting the nut down into a horizontal position on the standard. The screw 16, with the pin 18 in place, is then moved up through the bottom of the standard and threaded into the nut 22 by rotating the latter. A top saddle 45 may then be applied to the upper end of the lifting screw and riveted or otherwise held in place. The driving pinion 25 is then applied by slipping the cylindrical bearing portion into the bore of the standard lug 28 and the pin 34 is driven in place. When the

pinion 25 and the screw 16 are assembled, it will be apparent that any tilting movements of the nut 22 on the top of the standard will be prevented, and unless the nut 22 can tilt it cannot be removed. The interlocking parts of the nut on the standard being located about the point where upward force is applied to the nut by the driving pinion, provides for a direct resistance to the upward force applied to the peripheral portions of the lifting nut. When a load is engaged by the saddle of the lifting screw, it will be apparent that the entire nut is held down firmly on the top of the standard, and when there is no load on the jack it will be apparent that the upward thrusts on the peripheral portions of the nut, created by rotation of the driving pinion, are comparatively small so that they can readily be taken care of by the frictional engagement of the nut and the standard at the point where they are interlocking engaged.

It will be apparent that the disassembly of the jack parts may be accomplished very readily if the saddle is applied in a removable manner to the top of the lifting screw. Thus, the lifting screw may be threaded downwardly through the lifting nut, the holding pin 34 and the driving pinion removed, after which the operating nut may be readily removed from the top of the standard without disturbing any part of the standard itself, which can therefore be of integral rigid construction, the standard being preferably made as a single piece casting.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A lifting jack comprising a lifting screw, a standard telescopically receiving said screw, a nut in threaded engagement with said screw, the top of the standard being unsymmetrically formed so as to have a projecting portion thereon, the nut having provision for interlockingly engaging said portion providing for ready assembly of the nut but holding the nut against axial movement, and means for operating said nut.

2. A lifting jack comprising a lifting screw, a standard telescopically receiving said screw, a nut in threaded engagement with said screw, the nut and the end of the standard having interlocking portions providing for assembly of the nut in an inclined position before the lifting screw is threaded in said nut, the lifting screw when threaded in the nut preventing tilting movements of the nut to maintain the nut against axial movements with relation to the standard.

3. A lifting jack comprising a lifting screw, a standard telescopically receiving said screw, a nut in threaded engagement with said screw, the standard having a flat top surface, the nut extending down below the top of the standard and in bearing engagement with the standard below the top thereof, said nut having a groove provided at a point below the top of the standard, the standard having a lug projecting at one side only at the top of the standard to be received in said groove.

In testimony whereof I hereto affix my signature.
